LAUNDRY AGITATOR

Raymond M. Goodman, St. Joseph, and Robert S. Trem-bath, Benton Harbor, Mich., assignors to Whirlpool Corporation, Benton Harbor, Mich., a corporation of Delaware

Filed June 19, 1969, Ser. No. 17,775

Term of patent 14 years

Int. Cl. D15—07

U.S. Cl. D49—1

FIG. 1

FIG. 1 is a side elevation view of the laundry agitator showing our new design.

FIG. 2 is a top view thereof.

FIG. 3 is a side elevation view of the laundry agitator rotated 30° along a vertical axis from the position shown in FIG. 1.

We claim:

The ornamental design for a laundry agitator, as shown.
